TOBACCO BARN

John G. Long, William R. Long, and Philip J. T. Rawlins, Tarboro, N.C., assignors to Long Manufacturing Company, Tarboro, N.C.

Filed Nov. 2, 1962, Ser. No. 235,100

4 Claims. (Cl. 34—213)

This application is a continuation-in-part of application Serial No. 150,421, filed November 6, 1961.

This invention relates to the harvesting, handling and curing of tobacco including apparatus and equipment employed in such operation and designed to facilitate the accomplishment of the work and to reduce the amount of time and labor involved.

The invention relates particularly to a tobacco barn constructed for the curing of tobacco under controlled conditions of temperature and humidity and in which uniform high quality of the product is the goal.

The curing of tobacco has involved numerous problems including a barn in which the air was heated and circulated under controlled conditions of temperature and humidity to accomplish the drying or curing of the tobacco, it having been found desirable to add to the air within the barn fresh air from the exterior and to thoroughly mix the same as well as to insure the circulation of the air over the entire area within the barn.

It is an object of the invention to provide a barn of the character indicated with means for providing the necessary heated air, for admitting fresh air, for producing a thorough mixing of the fresh air with the circulating air within the barn, and for withdrawing air from remote corners and other areas and otherwise producing a thorough circulation of the air to insure uniform curing of the tobacco or other products to obtain the finest quality end product.

Another object of the invention is to provide a barn having a central curing room or area with a curing room or area at each side and means for admitting fresh air from the outside into the air within the barn and for thoroughly mixing it as it is admitted as well as providing such means in a manner that air will be withdrawn from remote corners and other areas of the barn insuring uniform temperature and humidity.

Another object of the invention is to provide a barn including a heating and duct system with control means for admitting fresh air from the exterior to be mixed with the heated air in the area and adding additional heat to produce complete treatment of an entire area under uniform temperature and humidity conditions.

A further object of the invention is to provide a tobacco barn in which the air is heated in a furnace located exteriorly of the area in which the product to be cured is contained and subjected to heat without excessive hot spots with means for admitting fresh air in a controlled amount as well as for circulating the air uniformly over the area in which the tobacco is contained while maintaining uniform temperature and humidity conditions.

Other objects and advantages of the invention will be apparent from the following description considered in connection with the accompanying drawings wherein:

FIG. 1 is a fragmentary perspective of the rear elevation view of a barn;

2

FIG. 2, a transverse section on the lines 2—2 of FIG. 1;

FIG. 3, a section through the furnace on lines 3—3 of FIG. 2;

5 FIG. 4, a fragmentary section on lines 4—4 of FIG. 3;

FIG. 5, a fragmentary rear elevation of the furnace showing the ventilating door operating means;

FIG. 6, a large fragmentary detail taken along lines 6—6 of FIG. 5; and

10 FIG. 7, a fragmentary detail of a section taken along the lines 7—7 of FIG. 5.

Briefly stated the barn of the present invention includes independent treating areas as, for example, a central curing room and a curing room on each side thereof all of which are independently heated from an exterior source of heat and with means for admitting and mixing fresh air with the contained air immediately prior to its being subjected to heat and with the connection between the source of heat and the curing rooms at the sides larger than that at the center to expose the side rooms to greater suction and cause the withdrawing of air from and the supply of air to remote corners of the rooms in which tobacco is treated, the barn having three separate compartments all supplied with heat from a single source outside the curing rooms.

With continued reference to the drawings, the barn has an outside foundation wall 10, with four sides which may be of substantially equal length. On the foundation wall 10 are supported relatively laterally spaced board-like members 11 (FIG. 3), which form the support for the raised perforated metal grill type floor 11' of the barn which forms the upper side of an enclosed space forming an airflow passageway to all parts of the barn

35 The barn is provided with a front support 12, left and right side walls 13 and 14, a pair of rear walls 15 and 15' and a roof 16. Within the barn there are a pair of partitions 17 and 18, which divide the interior into three rooms extending from front to rear, and each room being 40 provided at the front with a pair of doors 19. The partitions 17 and 18 are spaced from the top of the barn and extend downwardly to a position near and parallel to the floor and are vertically supported along their lower portions by upright studs (not shown). The entire 45 barn curing areas beneath and closely above the floor and adjacent to the roof are open to allow free horizontal air circulation.

Means is provided for supporting the tobacco or other products in the manner illustrated and described in the 50 abovementioned application, as well as the manner and equipment employed in the loading and unloading of the tobacco, the earlier application being considered a part hereof.

In order that the air within the barn may be modified 55 as to temperature and humidity and be circulated in the manner desired the area containing a furnace or heater unit is inset or recessed in the rear of the barn in a manner that it reduces the depth of the central curing room and is located between the two side curing rooms.

60 The furnace recess is formed by a front wall 21 and a pair of side walls 22 and 23 and with a full width opening 24 to the outside whereby the furnace is positioned entirely within the recess and can be controlled and serviced exteriorly of the barn.

Within the furnace recess is located a furnace comprising an upright wall or casing 25 providing a vertical airflow duct structure having a top 26, such furnace resting upon the floor 27 having a central opening 28 of a size corresponding to that of the opening at the bottom of the furnace.

Within the furnace is mounted a fire box 29 supported by brackets 30 and provided with a gun type burner 31. Above the fire box 29 is an inverted frusto-conical heat exchanger 32 mounted on upper and lower brackets 33 within the furnace chamber, which chamber is lined with insulation 34 within the upright wall or casing 25. Above the heat exchanger 32 is located a circulating fan 35 mounted on a shaft 36 carried in a protective tube 37 held in place by brackets 38 which engage the wall 25 of the furnace. The shaft 36 extends through the top 26 of the furnace and is driven by a motor 39.

Air from the central curing area of the barn is admitted or returned to the furnace through front duct 40 and from the side rooms through side ducts 41 and 42. Air drawn through the side ducts 41 and 42 is caused to travel downwardly in contact with the heat exchanger and then is discharged at the lower end of the furnace through the opening 28 to the airflow space beneath the floor where it impinges against a deflector 20 and is distributed in every direction and caused to evenly flow up through the grill type floor 11' and the tobacco therein (not shown) to be cured and be returned through the ducts 41 and 42 for reheating and recirculation.

In order to supply fresh air to be recirculated and to produce a thorough intermixing of the fresh and recirculated air the upper portion of the side wall 25 of the furnace is provided with fresh air openings 43 and 44 over the ducts 41 and 42 at opposite sides of the furnace and the amount of opening is controlled by adjustable closures 45 and 46 mounted on hinges 47 and 48. By the adjustment of the closures 45 and 46 the amount of fresh air admitted can be readily controlled and means is provided for simultaneously operating the closures 45 and 46 in the form of links 49 and 50 connected by pivots 51 and 52 with the closures 45 and 46. The inner ends of the links 49 and 50 are secured by pivots 53 and 54 to an operating link 55 attached to a central pin 56 joined to an operating bar 57 having a spring loaded detent 58 engaging a notched edge 59 of a curved bar 60 secured by fasteners 61 at its ends through the wall 25 of the furnace.

In the operation of the device fresh air admitted through the openings 43 and 44 travels downwardly and meets and mixes with air from the central curing room or area and the two side curing rooms or areas through the ducts 40, 41 and 42, respectively. The combined air is caused to travel downwardly by the fan 35 over the heat exchanger 32 whereupon it passes the restricted area at the lower extremity of the heat exchanger where its velocity is increased with less static pressure or in the manner of a venturi. As the products of combustion are withdrawn from the combustion chamber 29 beneath the heat exchanger 32, such products combine with the heated air and are forced downwardly and through the opening 28 in the floor and are distributed over the enclosed area beneath the floor and then upwardly through the several curing rooms, the temperature of the air being controlled by a thermostat.

The duct 40 is of smaller size than the ducts 41 and 42 in order that the suction through the side ducts will be proportionately greater to draw the air from the remote corners of the barn.

It will be apparent from the foregoing that a barn is provided in which a uniform operation is provided with regard both to temperature and humidity as well as the admission of fresh air and the thorough mixing of the fresh air with the heated air with the avoidance of hot spots.

It will be obvious to those skilled in the art that various changes may be made in the invention without departing from the spirit and scope thereof and therefore the invention is not limited by that which is illustrated in the drawings and described in the specification, but only as indicated in the accompanying claims.

What is claimed is:

1. A building structure for use in the curing of a harvested product such as tobacco, said building structure having a roof and side walls including an end wall, a foundation wall extending above ground and underlying all of said side walls of said building structure and providing an airflow space enclosed thereby above ground level throughout the entire area of said building structure, said end wall having an outwardly facing and completely open recess formed therein and extending throughout the vertical extent thereof, said outwardly facing end wall recess having a floor therein mounted on the top of said foundation wall, a heater unit mounted on said floor of said recess above and in communication with said foundation airflow space, said heater unit being exposed to and adapted for servicing and control thereof exteriorly of said building structure, the remainder of said building structure having a grill-type floor therein extending throughout the entire remaining enclosed area thereof overlying and forming an upper wall of said airflow space enclosed by said foundation wall, partition means dividing said remainder of said housing into multiple different sized curing areas in which tobacco is adapted to be contained, said heater unit mounted within said outwardly facing end wall recess having a vertical airflow duct means therein in completely open communication at the lower end thereof with said foundation airflow space, fresh air inlet means including adjustable closures therefore located in the upper portion of said vertical airflow duct means of said heater unit and disposed wholly within said outwardly open wall recess, differentially sized individual return flow air ducts in communication with said vertical airflow duct means positioned below and adjacent said fresh air inlet duct means and in communication respectively with each of said multiple different sized curing areas, said heater unit including means for heating and effecting direct axial downward flow of heated air therein into said foundation airflow space, means separate from said duct means and positioned within said foundation airflow space cooperative with said heater unit means for effecting lateral circulation of the heated air within said airflow space and up through said grill-type floor into all of said different sized multiple curing areas and for return thereof to said vertical airflow duct means of said heater unit through said differentially sized return flow ducts to maintain an even and uniform flow of the heated circulated air throughout the entire extent of the interior of said building structure.
2. The structure as defined in claim 1 wherein said grill-type floor is of perforated metal construction, said separate means in said airflow space for effecting circulation of air therein comprising angular air deflecting and guiding means located directly below said heater unit, said angular deflecting and guiding means being effective to minimize air turbulence within said foundation air flow space.
3. The structure as defined in claim 1 wherein said heater unit means and said vertical airflow duct means include a fan mounted axially thereof for effecting said direct axial downward flow and heating of the air therein,

motor means positioned exteriorly of said duct means for driving said fan,
and throat-forming means within said vertical airflow duct means of said heater unit effective for increasing the velocity therein of the downward flow of the 5 heated air into said foundation airflow space.
4. The structure as defined in claim 3 wherein said throat-forming means in said heater unit vertical airflow duct means comprises a frusto-conical heat exchanger mounted axially thereof,
and common manually operable actuator means including detent means accessible from the exterior of the building structure for simultaneously controlling the adjustable closures of said fresh air inlets of said heater unit airflow duct means.
